UNITED STATES PATENT OFFICE.

FREDERICK C. CROWE, OF SPOKANE, WASHINGTON.

PUMP.

1,169,243.

Specification of Letters Patent. Patented Jan. 25, 1916.

Application filed July 2, 1914. Serial No. 848,590.

To all whom it may concern:

Be it known that I, FREDERICK C. CROWE, a citizen of the United States, residing at Spokane, in the county of Spokane and 5 State of Washington, have invented certain new and useful Improvements in Pumps, of which the following is a specification.

The object of this invention is to provide an improved pump structure which involves 10 an improved form of pump and a novel construction of water motor for operating the pump, the invention residing in the combination of the two and also in the pump and water motor as separate entities of 15 invention.

As a water motor, my invention includes a motor bucket or receptacle tiltably supported in a running stream in such a manner as to be filled with water on one tilting 20 movement, so as to be actuated by the weight of the water to tilt the receptacle into another position, means being provided for causing discharge from the receptacle when the latter is moved under the weight of its 25 contents.

A further object is to provide an improved pump structure for operation by said motor, said pump structure embodying a pump proper and a dash pot device in connection therewith, whereby the pump structure may function to control operation of the motor.

Other features and objects of the invention will be more fully described in connection 35 with the accompanying drawings, and will be more particularly pointed out in and by the appended claims.

In the drawings: Figure 1 is a view in side elevation with the greater portion of 40 the structure in section, showing one form of the device of my invention interposed in a running stream. Fig. 2 is a view similar to Fig. 1 with the parts in a different position. Fig. 3 is a view in elevation looking 45 from the left of Fig. 1. Fig. 4 is a sectional view on line 4—4 of Fig. 1. Fig. 5 is a sectional view on line 5—5 of Fig. 4. Fig. 6 is a view in elevation of a valve controlling member forming a part of my invention.

50 Like characters of reference designate similar parts throughout the different figures of the drawings.

That part of the structure of my invention which relates to the water motor is particularly designed for operation in a running stream at a point where the bed affords

a declivity, as indicated at 1, with respect to the bed 2, above such point. However, in the absence of a natural declivity, my invention may be disposed adjacent a dam, as 60 indicated by dotted lines 3.

Referring more particularly to the structure illustrated, 4 indicates a motor bucket or receptacle having an open ingress end 5, which may comprise a normally open portion of an end wall 6, a closed end 7, and is provided with an opening 8 which may be formed in the bottom wall 9 of the bucket. A valve closure 10 is shown pivoted at 11 to the bottom wall 9 in such a manner that 70 the contents of the bucket will act to maintain the closure 10 in a position to close the opening 8.

Means is provided for tiltably mounting the motor bucket between its ends in such proximity to the running stream that when its ingress end is lowered into the position shown in Fig. 1, the bucket will take water from the stream to tilt the bucket, by the weight of the water, into the position shown in Fig. 2, wherein the ingress end will be elevated above the surface of the water in the stream. As illustrated, such means is in the form of a frame embodying horizontal longitudinal members 12 supported by front 75 and rear uprights 13 and 14, respectively, and connected by front and rear transverse members 15 and 16. Depending from the horizontal member 12 are hangers 17 in which a hanger shaft 18 is journaled, the 80 hanger shaft 18 being suitably connected with the side walls of the motor receptacle or bucket 4 in a manner to pendants support the same in the manner shown. In order that the weight of the contents of the 85 bucket may act more responsively and positively to tilt the same and to also afford a greater leverage, I dispose the hanger shaft 18 more closely to the ingress end 5 than to the egress end 7, although this is not absolutely essential in view of the fact that water rushing toward end wall 19 would always act to tilt the bucket into a discharging position because of the accumulating weight of water at the egress end resulting from abrupt stoppage of the current by end wall 19. In 90 the present construction, the center of gravity of the bucket is toward the discharge end with respect to the tilting shaft 18, and in order that the bucket may be returned to an intake position, as shown in Fig. 1, from the 95 position shown in Fig. 2, I provide means

100

105

110

which may be a counterweight and which may comprise a chamber 20 adapted to be filled with sand, gravel or other suitable material 21. In order to limit movement of the bucket 4 under its counterweight beyond the position shown in Fig. 1, I may provide means such as a chain 22, which may have an interposed spring 23 to neutralize shock, the chain being suitably fastened to the frame-work, as indicated at 24 and to the bucket as indicated at 25.

In order to gain the fullest advantage of power, I provide a valve operating means for controlling egress of the contents from the bucket, which is adapted to quickly open the bucket for discharge when the latter has approximated the limit of tilting movement in one direction, such means including, in the preferred construction, a lost motion connection.

As shown, a link 26 is pivoted at 27 to valve closure 10 and is pivoted at 28 to a valve operating arm 29. Arm 29 is pivoted at 30 to the bucket 4, and nearer to pivot 30 than to pivot 28, I pivotally connect at 31, one member 32 of my improved lost motion connection. Member 32 is provided with a pin 33 which is slidable in a slot 34 formed in the other member 35 of said lost motion connection. Said slotted member 35 is pivoted at 36 to the supporting frame. Now it will be seen that the pin 33 will travel throughout the length of slot 34 before arm 29 is actuated, on descent of the discharge end 7, to open closure 10, and it will be further noted, that the quick opening and what may be termed as the delayed opening of closure 10 will be further increased or retarded by the disposition of the pivot 31 in such close adjacency to pivot 30. When the valve closure 10 is finally opened, it will not only be quickly opened but it will also be fully opened so as to give a sudden and full capacity discharge for the contents of the bucket. It will further be noted that the path of the water through the bucket is in the same general direction as the current of the stream and thereby full advantage of stream power is utilized. Of course, it will be understood that power may be taken from this motor for any purposes desired, and while I have shown the same connected up with a pump structure, I do not wish to be limited to this association, although it will be understood by the following description that the novel form of pump structure provided, patently coacts interdependently with my improved motor.

A pump cylinder 37 is interposed in the stream and may be anchored in any suitable manner and which is provided with an intake pipe 38 and an outlet pipe 39. The intake pipe 38 is provided with a non-return valve comprising a casing 40 having a valve closure 41 which is arranged to

open toward the cylinder and close in movement away from the cylinder. A pipe 42 may lead from the casing 40 into the stream for entrance of water into cylinder 37. The outlet pipe 39 is provided with a non-return valve casing 43 having a hinged closure 44 arranged to open away from cylinder 37 and close toward cylinder 37. A delivery pipe 45 leads from casing 43 to any point of disposition for the pumped water. A piston 46 is arranged to reciprocate in cylinder 37, and the piston may be provided with flap valves 47 for closing passages 48 on upward strokes of the piston, to discharge through outlet 39, the flaps 47 opening on downward movement of the piston 46 to permit supplied water to pass the piston and flow into the upper part of the cylinder 37. A piston rod 49 is connected with piston 46, at one end of said rod, the other end of said rod extending through an air controlling cylinder 50 and being connected with piston 51, which is reciprocable in said cylinder 50. In order to prevent vacuum interference against operation, I provide an escape valve 52, which will normally be open to a limited extent and which is connected with the upper end of cylinder 50 to permit of limited ingress and egress of air.

The working or upward stroke of piston 46 will impose some load of a considerable nature on the motor, but I also provide air controlling valve means whereby movement of the piston 51 may be controlled to obtain the proper stroke of piston 46. As illustrated, a valve casing 53 is connected with and communicates with cylinder 50 and is provided with an outlet 54, which may include an outlet pipe 55. Interposed in the casing 53 between cylinder 50 and outlet 55 is a valve closure which may be of the rotating type and which is shown in the form of a cap 56 provided with an opening 57 adapted to be brought into and out of registry with outlet 55. A stem 58 extends upwardly from the cap valve 56 through the casing 53 and carries a radially extending arm 59. The rod structure 49, connecting pistons 46 and 51 is preferably formed in two parts comprising the pump rod 49 and the dash pot rod 60, the latter being directly connected with piston 51. The dash and pump rods are shown pivoted at 61 and 62 with links 63 and 64, respectively. An arm 65, secured to the motor bucket 4, rigidly, is pivoted at 66 to links 63 and 64, whereby the said links are connected to form a piston rod structure operatively connecting the pistons of both cylinders. On the dash rod 60, I adjustably mount by means of a collar 67 fixed by a set screw 68, a controlling valve operating member 69. Said operating member 69 is held to a linear path of movement by a

guide 70', which may be secured to dash cylinder 50. The upper end of member 69 is flattened and is provided with a cam which may be in the form of a slot having 5 an elongated closing portion 70 and a relatively short opening portion 71 connected by an intermediate actuating portion 72. Arm 59 projects into said slot and on reciprocating movement being imparted to 10 said member 69 there will be rotary movement imparted to arm 59 to open and close the controlling valve.

Assuming that the motor bucket or receptacle is in the position shown in Fig. 1, and 15 the water is rushing into the same, it will be clear that the bucket will not descend with the same force with a slight quantity of water therein as it would with a considerable quantity because the water would not 20 only have to overcome the counterweight but also the load imposed in operating the pump piston. Therefore, the slow egress or leakage of air through valve 52 will cause the piston 51 to rise very slowly, at the 25 start, thereby insuring an effective fill of the bucket, so as to get the greatest amount of pumping power. As the bucket lowers and the piston 51 and operating member 69 rise to a point where the operating portion 30 or cam 72 reaches arm 59, then valve 56 will be relatively quickly opened into full registry with exhaust 55 whereupon the only resistance to movement of the bucket will be imparted by the pump, and therefore the 35 bucket will descend to the position shown in Fig. 2 relatively quickly under the weight of a maximum amount of water. Just before the completion of the downward movement of the egress end of the bucket 4, the 40 pin 33 reaches the lower end of slot 34, thereby opening valve 10. After the valve 10 is opened, water is discharged and the counterweight 21 will return the bucket to the position shown in Fig. 1 and because of 45 the greater length of slot portion 70, there will be a free admission of air into dash cylinder 50 during the greater portion of the descent of piston 51. Furthermore, any resistance against descent of piston 46 will 50 be neutralized by free passage afforded by flap valves 47. During a short final portion of the return movement to the position shown in Fig. 1, valve 56 will be practically closed, but this will be at a time when the 55 counterweight has the greatest leverage.

It is believed that the advantages and utility of my invention will be clearly understood from the foregoing description, and while I have herein shown and described one specific form of my invention, I do not wish to be limited thereto except for such limitations as the claims may import.

I claim:

65 1. In a water motor for streams, a motor

bucket having an open ingress end and an egress end, means tiltably supporting said bucket between its ends with its ingress end opening toward the current, a valve for the egress end of said bucket, counterweight 70 means normally acting to lower the ingress end into the stream to fill the bucket and cause the latter to thereafter tilt under the load of the contents to elevate the ingress and lower the egress end, and means for opening said valve to empty the bucket on descent of the egress end thereof, substantially as described.

2. In a water motor for streams, a motor bucket having an open ingress end and an egress end, means tiltably supporting said bucket between its ends with its ingress end opening toward the current, a valve for the egress end of said bucket, counterweight 80 means normally acting to lower the ingress end into the stream to fill the bucket and cause the latter to thereafter tilt under the load of the contents to elevate the ingress and lower the egress end, and means for quickly opening said valve just prior to the 85 limit of descent of the egress end of said bucket, substantially as described.

3. In a water motor for streams, a motor bucket having an open ingress end and an egress end, means tiltably supporting said 95 bucket between its ends with its ingress end opening toward the current, a valve for the egress end of said bucket, counterweight means normally acting to lower the ingress end into the stream to fill the bucket and 100 cause the latter to thereafter tilt under the load of the contents to elevate the ingress and lower the egress end, and a lost motion connection between said valve and supporting means for opening the former on descent of the egress end of said bucket, substantially as described.

4. In a water motor for streams, a motor bucket having a normally open ingress end and an egress end, means connected with 110 the bucket nearer the ingress than the egress end for tiltably supporting the bucket with the ingress end opening toward the current, a valve for the egress end of said bucket, means normally acting to lower the ingress 115 end into the stream to fill the bucket and thereby cause the contents to tilt the egress end downwardly, and means for opening said valve to empty the bucket on descent of the egress end thereof, substantially as described.

5. In a combined water motor and pump, a reciprocating pump structure disposed in a stream and having a pump piston rod structure, a dash pot piston and a dash pot 125 cylinder therefor with the dash pot piston connected with said rod structure, a valve for controlling egress from said dash pot cylinder, an operating member actuated by said rod structure for operating said valve, 130

and a water motor operated by said stream for actuating said rod structure, substantially as described.

6. In a combined water motor and pump, 5 a reciprocating pump structure disposed in a stream and having a pump piston rod structure, a dash pot piston and a dash pot cylinder therefor with the dash pot piston connected with said rod structure, a valve 10 for controlling egress from said dash pot

cylinder, an operating member actuated by said rod structure for operating said valve, and means for operating said rod structure, substantially as described. 15

In testimony whereof I affix my signature in presence of two witnesses.

FREDERICK C. CROWE.
